UNITED STATES PATENT OFFICE.

LEO J. WERNER, OF ARLINGTON, NEW JERSEY, ASSIGNOR TO SPLITDORF ELECTRICAL COMPANY, OF NEWARK, NEW JERSEY.

IGNITION SYSTEM.

1,304,835.

Specification of Letters Patent. Patented May 27, 1919.

Application filed September 30, 1918. Serial No. 256,218.

To all whom it may concern:

Be it known that I, LEO J. WERNER, a citizen of Russia, residing at Arlington, in the county of Hudson and State of New Jersey, U. S. A., have invented certain new and useful Improvements in Ignition Systems, of which the following is a specification.

This invention relates to an ignition system adapted for use on large, high compression engines which are hard, or not adapted to be started, with a hand crank, but which are started "on compression." It is particularly adapted for use in connection with engines used on airplanes that are usually started by priming the cylinders or drawing in charges of fuel by turning the engine over, through the medium of the propeller, at which time the ignition system is out of operation. It is usual to equip such engines with duplicate ignition generators and a double set of spark plugs for the purpose of getting the maximum power out of the engine and increasing the reliability. After the engine has been primed, as above set forth, ignition is usually obtained through the operation of a hand starting ignition generator which supplies the initial ignition impulse or impulses, while the service ignition generators and engine are at rest. Several schemes have been used, one of which involves the use of a high tension starting ignition generator which supplies secondary current to the engine spark plugs through the medium of a trailing brush in the distributor of one or both of the service generators, at a period of time somewhat later than the service generator. Another scheme is to provide a low tension starting generator, that is, one having a low tension winding only, and connect this generator to the primary of the service generators which are preferably of the high tension type. The introduction of current from the low tension starting generator into the primary of either of the service generators causes the secondary winding to produce a spark in the cylinder adapted to receive it. In many ways this latter scheme is preferable to the first, in that the starting generator is simpler to make, on account of one low tension winding, and is less likely to "break down" or get out of order. My invention relates particularly to a system of the latter kind and is directed to certain improvements therein.

After the engine has been started, it is

highly advantageous to be able to switch "off" and "on" either one of the service ignition generators in order to see that the other one is firing the engine properly, after which test has been made the controlling switch is so thrown that both service generators are in "commission."

In certain arrangements using the low tension starting generator in the combination as above set forth, trouble has been experienced, due to the fact that at the time the engine is started the starting generator winding is left connected with the primary winding of one of the service generators and this will function to a considerable extent through the starting generator winding as the circuit breaker or controller of the latter generator may stop in open position so that the proper test cannot be obtained on either of the service generators.

It is the principal object of my invention to provide means to eliminate this trouble by a comparatively simple mechanism used on the starting generator.

In the drawings, which are attached to and form a part of this specification, Figure 1 is a side elevation of the starting generator with the hand operating mechanism in the "off" or inoperative position.

Fig. 2 is a partial view of the generator of Fig. 1 but with the starting mechanism in operative position.

Fig. 3 is an end view of Fig. 1 with a part of the starting mechanism removed.

Fig. 4 is a perspective view of that part of the starting mechanism removed from Fig. 3.

Fig. 5 is an end view of the starting generator showing a modified form of part of the starting mechanism.

Fig. 6 is a vertical sectional view on the line 6-6 of Fig. 3, but with the mechanism of Fig. 4 in position.

Fig. 7 is a diagrammatic view of my ignition system.

Referring now to the details, wherein like numbers refer to corresponding parts in the various views, 1 illustrates a generator, preferably of the permanent magnet type, having a rotor shaft 2 which, in my preferred form carries rotors 3 and 4 which operate in a well known manner between field poles carrying the generating winding 5. A gear 6 is carried on the shaft 2 and meshing with it is another gear 7 having an operating handle 8. Gear 7 is supported on a bearing 9 attached

to the end plate 10. Fastened to the back of the gear 7, as by screws 11, is a member 12 to the rear end of which is made integral, or fastened thereto in any suitable manner, 5 a portion having a series of indentations 13. Within the member 12 and supported on the hub 14 is a spring 15 which bears against the end plate 10 thus serving to hold the gear 7 in its outward position on the bearing stud 10 9, as shown in Fig. 1. Mounted on support studs 16 and 17, attached to the end plate 10, are two arms 18 and 19 carrying members 20 and 21, preferably of the roller type, which are adapted to engage the indentations 13. 15 The upper ends of the members 18 and 19 are held in their proper operating relation by spring member 22.

As shown in the diagrammatic arrangement in Fig. 7, the rotors 3 and 4 are of the 20 two lobe type so that the starting generator is capable of delivering four current impulses per revolution of the shaft 2. Mounted within the breaker or controller end 23 of the generator 1 is the usual circuit breaker or controller 25 having a stationary member 24 and movable member 25 and cam 26 which is adapted to operate the movable member 25 four times per revolution to correspond with the current impulses generated by the generator. The 30 generating winding 5 is connected to the stationary and insulated contact 24 and a condenser 27 is connected across the controller in the usual way. 28 and 29 illustrate two service generators, preferably of the 35 high tension magneto type, each having primary windings P and secondary windings S with circuit breakers or controllers C and condensers K. 30 is a controlling switch having contacts 31 and 32 which are connected together and to the primary of the 40 generator 28. 33 and 34 are two contacts connected together and to the primary of generator 29. The stationary contact 24 of the starting generator is connected to a segment 35. 36 illustrates a switch lever carrying switch blades 37, 38 and 39 which are all electrically connected together. 40 is a ground contact.

Coming now to the operation of my ignition system, let it be assumed that the service generator 28 is chosen for the one to start the 50 engine. In operation, the operator on taking hold of the handle 8 of the starting generator pushes it inward against the spring 15 moving the gear 7 toward the plate 10 so that the indentations 13 pass beyond engagement of the members 20 and 21, as shown in Fig. 2, thus removing the friction which would be produced by the engagement of 55 members 20 and 21 with the indentations 13. Turning the gear 7, which I preferably make with about four times as many teeth as in gear 6, will turn the rotors 3 and 4 rapidly generating the current in the winding 5 which will be acted on by the controller mem-

bers 24 and 25 to send rapid impulses through the primary P of the generator 28, it being assumed that the switch 30 is thrown to the position shown. As soon as the engine starts the operator ceases to operate the 70 starting generator and as soon as the hand is removed from the handle 8 the spring 15 returns the gear 7 to the position shown in Fig. 1 which brings the indentations 13 back to their normal position so as to be engaged 75 by the members 20 and 21, which, due to the tension of the spring 22 on the arms 18 and 19, will act to turn the gear 7 and the shaft 2 so that the contact 41 will be brought into closed position, it being understood that the 80 number of indentations 13 are chosen in the right proportion to the cam 26 to produce this result. Now, since the starting generator is always stopped so that the contact 41 is closed it will be seen that the winding 5 85 is short circuited through the controlling arm 25 and the primary winding of the service generator 28 will be permanently and positively grounded so that the generator 29 will furnish the ignition for the engine hence 90 the operator will have a test on this particular generator. The switch arm 36 can now be thrown to the position A—B where it will be seen that the starting generator is connected to the service generator 29 and the 95 service generator 28 will furnish all of the ignition current. When the switch lever 36 is thrown to the position C—D both service generators 28 and 29 are furnishing current. When it is desired to stop the engine the 100 switch lever 36 is thrown to the position E—F where it is seen that both generators 28 and 29 are grounded and put out of action in the usual way.

In the modified form of mechanism shown 105 in Fig. 5 the plungers 42 and 43 take the place of the mechanism shown in Fig. 3 and function in an equivalent manner.

While I have shown a starting generator of one particular type, it will be understood 110 that other types of generators are capable of being used and while I have shown certain details of starting mechanism, I do not wish to be limited to the exact forms shown and described.

Having thus described my invention, what 115 I claim is:—

1. An ignition system for internal combustion engines comprising ignition means including a service generator driven by the 120 engine and having primary and secondary windings for furnishing sparking current, a starting generator having a generating winding, means for connecting said winding to the primary of the service generator for delivering current thereto, and means for stopping the starting generator in a predetermined position for the purpose described.

2. An ignition system for internal combustion engines comprising ignition means 125

including a service generator driven by the engine and having primary and secondary windings for furnishing sparking current, a starting generator having a generating winding, and a controller to control said winding, means for connecting said winding to the primary of the service generator for delivering current thereto and means for automatically stopping the starting generator in such a position that the controller renders said generating winding inert.

3. In an ignition system for internal combustion engines comprising ignition means including service generators driven by the engine and each having primary and secondary windings for furnishing sparking current, a starting generator having a generating winding, switching means for connecting said winding to the primary of either of the service generators for delivering current thereto and means for stopping the starting generator in a predetermined position so that the service generator to which it is connected is positively rendered inoperative.

4. In an ignition system for internal combustion engines comprising ignition means including service generators driven by the engine and each having primary and secondary windings for furnishing sparking current, a starting generator having a generating winding, and a controller to control said winding, switching means for connecting said winding and controller to the primary of either of said service generators for delivering current thereto and means for automatically stopping the starting generator in such a position that the controller renders inert its generating winding as well as the generating windings of the service generator to which it is connected.

5. An ignition system for internal combustion engines comprising ignition means including service generators driven by the engine and having primary and secondary windings for furnishing sparking current, a starting generator having a generating winding, means for connecting said winding to the primary of either of the service generators for delivering current thereto, an operating pinion on the starting generator, a starting gear operatively connected to said pinion and carrying means constructed to be automatically acted on to turn said starting gear and means carried on the frame of said generator for engaging the said means in the starting gear to move it and the driving

pinion automatically to a predetermined position for the purpose described.

6. An ignition system for internal combustion engines comprising ignition means including service generators driven by the engine and having primary and secondary windings for furnishing sparking current, a starting generator having a generating winding, and a controller to control said winding, means for connecting said winding to the primary of either of the service generators for delivering current thereto, gear wheels on the starting generator for operating the generator and said controller, one of said gears carrying means to be acted on manually and automatic means carried on said generator for acting on said gear wheel after the manual force has been removed for operating the controller so as to render inert the starting generating winding as well as the service generator windings to which it is connected, for the purpose described.

7. An ignition system for internal combustion engines comprising ignition means including a service generator driven by the engine and having primary and secondary windings for furnishing sparking current, a starting generator having a generating winding, means for connecting said winding to the primary of the service generator for delivering current thereto, manual means for operating the rotative parts of the starting generator and automatic means for positively positioning said rotative parts in one of certain predetermined positions for the purpose described.

8. An ignition system for internal combustion engines comprising ignition means including a service generator driven by the engine and having primary and secondary windings for furnishing sparking current, a starting generator having a generating winding, means for connecting said winding to the primary of the service generator for delivering current thereto, manual means for operating the rotative parts of the starting generator, automatic means for positively positioning said rotative parts in one of certain predetermined positions after the manual force has been removed, said automatic means being disarranged by the manual means to render operation of the rotative parts of the generator easier as described.

In witness whereof, I affix my signature.
LEO J. WERNER.
